SCOOTER

Gerhard J. Ohlhaver, St. Clair Shores, Mich.

Application March 18, 1947, Serial No. 735,298

1 Claim. (Cl. 280—16)

1

This invention relates to a scooter and, in particular, it relates to a scooter or push-vehicle adapted for use on snow or ice. More particularly, the invention relates to a scooter having, in combination, sleigh-runners, ski-runners and ice-runners.

In general, my invention relates to a scooter, the principal body of which comprises a ski-surface or runner, a portion of which is steerable for directional control. Permanently affixed to the sides of the ski-board are sleigh-runners which are particularly adaptable for supporting the vehicle on hard snow or ice. The sleigh-runners extend only a short distance below the bottom surface of the ski-board, thus the sleigh-runners do not detract from the operation of the vehicle over soft snow. In fact, the sleigh-runners function to maintain the ski-board in a straight path unless it is deviated from that path by means of the steering mechanism. Adjacent to the sleigh-runners, but of a lesser length, are ice blades adapted to be lowered slightly below the bottom of the sleigh-runners so that the scooter functions with great stability on hard ice in substantially the same manner as conventional ice skates. By this arrangement it is possible to use the scooter over a wide variety of surface conditions prevalent during the cold season.

It is therefore among the objects of my invention to provide a scooter of the character described which may be efficiently operated over loose snow in substantially the same manner as the operation of skis; to provide a scooter which in combination with operation over loose snow is also adapted through the medium of a different running surface to operate more efficiently over hard snow; to provide a scooter which in combination with its use on hard or soft snow is adaptable for use on hard ice; to provide a scooter of the character described which is readily steerable while being moved over various surfaces occurring in the winter months; to provide a scooter of the type described which is readily adaptable for use over hard or soft snow without any change in the runner arrangement; and, to provide a scooter of the character described which operates efficiently and which may be manufactured economically.

These and other objects and advantages will appear more fully in the following detailed description when considered in connection with the accompanying drawing, in which:

Figure 1 is a plan view of a scooter representing an embodiment of my invention;

2

Figure 2 is a side elevational view thereof, partly broken away;

Figure 3 is a transverse view, in section, of a portion of the scooter taken along lines III—III of Figure 2;

Figure 4 is an enlarged view, partly broken away, of a portion of the scooter illustrating the ice blade arrangement; and

Figure 5 is a view, in section, comparable to Figure 3 but illustrating a modified form of my invention.

With reference to the drawing and in particular to Figure 1, I illustrate a form of my invention constituting a scooter of which the principal base member constitutes a flat ski-member 1. Directly in front of the ski-member 1 is a continuation member 2. The leading edge of the continuation member 2 is bent upwardly so that the combination of both ski-members are proportionally equivalent to the conventional ski except that the width of the present embodiment is slightly greater than the width of the conventional ski. Preferably, the ski-members 1 and 2 are formed of wood.

The continuation member 2 is steerable in relation to the principal ski-member 1. This is accomplished by means of a bracket 3 attached near the leading edge of the member 1. A bracket 4 is attached near the rear edge of the ski-member 2 and is pivotally connected to a steering post 5. A flange bracket 6 is welded or otherwise associated with the steering post 5 and, by means of a hinge pin 7, the brackets 6 and 3 are pivotally connected together. This arrangement completes the steering mechanism between the ski-members 1 and 2. Handle bars 8 attached to the steering post 5 provide manual means for actuating the steering post 5.

Since the steering post 5 is pivoted with the ski-member 2 it is desirable to maintain the ski-member 2 in substantially the same plane as the ski-member 1. This is accomplished by means of a wire and spring 9 which attaches the leading edge of the ski-member 2 with the steering post 5. This connection prevents the leading edge of the ski-member 2 from pivoting downwardly particularly when the ski-member 2 is raised from a supporting surface.

Because a scooter of this type is usually used over various surfaces which may injure the material of the ski-members 1 and 2, I provide a sheet metal facing 10 and 11 applied to the under surface of the ski-members 1 and 2, respectively.

On each side of the ski-member 1 beginning at its rear edge and extending substantially one-

half of the length of the ski-member 1, I provide sleigh-runners 12 and 13. These runners are metal and form a right angle in cross-section and are provided with a flat portion for engagement with a riding surface. This flat portion extends about one inch below the bottom surface of the ski-member 1. Good results can also be obtained by maintaining the bottom surface of the sleigh-runners from one-half to one and one-half inches below the bottom surface of the ski-member 1. The forward end of the sleigh-runners 12 and 13 are curved upwardly so as to constitute a better approach to irregularities on the supporting surface. The sleigh-runners 12 and 13 may be attached to the sides of the ski-member 1 by any conventional means such as wood screws 14.

A somewhat similar set of sleigh-runners 15 and 16 are attached to the sides of the ski-member 2. Similarly, these sleigh-runners extend from the rear of the ski-member 2 to substantially one-half its length.

In operation over hard snow the sleigh-runners take precedence as a supporting medium for the scooter. This results in less friction and better controllability due to the steering arrangement. When the scooter is operated over soft snow the rather shallow depth of the sleigh-runners sink into the soft snow and do not materially affect the operation of the scooter in its ski function. In fact, when in use over soft snow, such as traveling downhill, the presence of the sleigh runners give better controllability to the scooter particularly insofar as steering is concerned.

When the scooter is in use on hard ice, means are provided in the form of ice blades 17 and 18 attached to the sides of the ski-member 1 in slots 19 and 20, respectively, provided therefor. In length, these ice-runners are comparable to conventional ice skates. The leading edge of the ice runner is pivotally connected to the side of the ski-member 1 and the rear portion of each ice-member is provided with a slot 21 for association with a bolt 22 extending through the width of the ski-member 22 and which may be tightened by means of a thumb nut 23.

A substantially similar pair of ice-runners 24 and 25 are associated with the ski-runner 2.

When it is desirable to use the ice-blades when operating over hard ice the operator merely loosens the thumb nut 23 to permit the runners to drop below the bottom surface of the sleigh-runners. The ice-runners are then tightened in place. It is merely necessary that the ice-runners extend to about one-eighth inch below the bottom surface of the sleigh-runners. Preferably, the bottom edge of the ice-runners are beveled so as to present a sharp edge to the ice surface.

To complete the assembly it is desirable to attach a second board 26 on top of the ski-member 1. This board is wider than the ski-member 1 and enables the operator to place both feet on the board 26 for coasting or for riding downhill. A raised portion or molding 27 adds to the ap-

pearance of the scooter and also functions as a stop to prevent the foot from sliding forward.

Figure 5 illustrates a modification of my invention and shows a device similar in all respects to the principal embodiment, except, that in place of the sleigh-runners and ice-runners, a single metal channel member 28 extends centrally along the length of the ski-members such as 29. Bolts 30 are used to attach the channel-member to the ski-member. The bottom edges 31 of the channel-member are beveled so as to present a semi-sharp edge. The unit is complete by the addition of a sheet metal facing 32 attached to the underside of the ski-member 29. This modified form is advantageous in that it is functional as a complete unit for operation in soft snow, hard snow, or on ice, and, in addition, it permits a slight amount of side tilting which may be effectively used in the performance of the scooter.

It is therefore believed apparent that I have provided a novel arrangement for a scooter which gives it wide utility in operation over various surfaces prevalent during the winter months.

While I have shown and described a preferred embodiment of my invention, it is to be understood that it is susceptible of those modifications which appear obviously within the spirit of my invention and as appearing in the scope of the appended claim:

Having thus described my invention, what I claim and desire to protect by Letters Patent is:

A vehicle of the general type of a scooter adapted for sliding engagement with a supporting surface comprising, a flat elongated body member constituting means for resting upon a slippery surface, a second flat body member positioned in front of the first named body member and forming a contiguous surface therewith, a runner positioned at each side of both the first and second named body members, an ice blade positioned at each side of both the first and second named body members, said ice blades having their bottom edges extending below the bottom surfaces of said runners, means for moving the ice blades and for locking them in a position wherein their bottom edges do not extend below the bottom surfaces of said runners, and means for swinging the second named body member relative to the first named body member for steering the vehicle.
